United States Patent Office

Des. 196,582
Patented Oct. 15, 1963

196,582

TILE

Jack A. Veerman, New York, N.Y., assignor to Amsterdam Corporation, New York, N.Y., a corporation of New York

Filed Jan. 27, 1961, Ser. No. 63,721

Term of patent 7 years

(Cl. D18—2)

Fig. 1

Fig. 2

Fig. 3

Fig. 4

FIG. 1 is a top plan view of a tile, showing my new design; FIG. 2 is a sectional view taken on line 2—2 of FIG. 1; FIG. 3 is a sectional view taken on line 3—3 of FIG. 1; and FIG. 4 is a fragmentary top perspective view thereof.

The top of the tile is shaded to show color contrast.

I claim:

The ornamental design for a tile, substantially as shown and described.
